TOY MOVIE

Charles O. Walls, Upper Darby, Pa.

Application June 6, 1945, Serial No. 597,851

1 Claim. (Cl. 46—13)

1

This invention relates to toys, and has for its primary object the provision of a device capable of affording children not only amusement and entertainment, but what is just as important, if not more so, useful instruction.

Another object of importance is to provide a toy capable of appealing to a child's natural curiosity, and of stimulating his inherent but latent learning and creative faculties.

Another important object is to provide a toy capable of being operated and of being taken apart and put together by a young child with little or no previous instruction.

Another important object is to provide a toy of relatively simple, inexpensive, rugged construction, capable of withstanding the type of rough usage to which children's toys are invariably subjected.

In its broadest essential aspects, the toy of the invention consists of a casing having a window in a wall thereof, a drum mounted within said casing, the cylindrical surface having depicted thereon either in pictures or words or both a series of related items such as events of a story, a sequence of cartoons, or lines of a poem such as a nursery-rime, etc., and means manually to rotate the drum so as to bring the items in registration with the windows in sequence.

For convenience of reference, the related items will be referred to as "continuity," or "sequence of events."

In the preferred embodiment of the invention, the continuity or sequence of events is printed, painted, or otherwise depicted on a strip of paper, fabric, or other suitable material, and "the continuity strip" may advantageously be detachably secured to the drum so that it may be readily replaced with another continuity by a child.

The underlying inventive concept is susceptible of being embodied in a number of different mechanical forms, one of which is being shown in the accompanying drawings for illustrative purposes. The following is a brief description of said drawing:

Figure 1 is a perspective view, partly broken away, of the illustrative embodiment of the invention;

Figure 2 is a vertical cross-section taken on line 2—2 of Figure 1, and looking in the direction of the arrows;

Figure 3 is a perspective view, partly broken away and partly in section, on a larger scale, of the drum which carries the continuity to be exhibited, and

Figure 4 is a perspective view of a continuity

strip, which may be used with the device of the invention.

As shown in Figures 1 and 2, the casing for the device of the invention may be in the form of a rectangular box having the body portion 11 and the removable flanged cover or lid 12. One of the walls, which is preferably but not necessarily the front wall, is provided with an opening or window 13. The box may be decorated in any suitable manner in keeping with the purpose of the device, and a desired title or name may be inscribed thereon. For example, the title "Kiddie Movies" is shown printed below the opening or window 13. The casing may be made in whole or in part of any suitable material such as paper, cardboard, wood, plastic, or metal.

The drum for carrying the continuity is denoted generally by 14, and consists essentially of the open-ended cylinder 15, and the two flanged covers or lids 16 and 17. The upper lid or cover 16 is preferably removable, whereas the bottom lid or cover 17 is preferably permanently secured to the cylinder. Extending through the centers of the two covers 16 and 17 is a cylindrical rod 18, which serves as the shaft or axis of rotation for the drum. The rod 18 is preferably secured or fixed to the lower cover 17, and passes freely through an aperture 19 in the upper cover 16. A washer 20 may be provided about the aperture 19. The means for securing the lower end of the rod to the lid 17 may advantageously take the form of the element 21, which has the cylindrical upper portion 22 and the conical lower portion 23. The element 21 is secured to the bottom cover 17 with its cylindrical portion 22 extending through an aperture in said cover, and the lower end of the rod extends into and is secured to the cylindrical portion 22.

The conical portion 23 of the element 21 constitutes part of the means for mounting the cylindrical drum for rotation within the casing 11. The numeral 24 denotes a bearing block, which is mounted on a horizontal partition 25 spaced from the bottom of the box 1. The upper surface of the bearing block is provided with a conical recess 26, which is adapted to receive the conical portion 23 of the element 21. The numeral 27 denotes a cross-piece which is provided with an aperture 28 for receiving the upper end of the cylindrical rod or shaft 18. The cross-piece 27 is supported from two opposite walls of the casing 11 by means of the brackets 29, 29'.

The drum may be rotated about the shaft 18 in a suitable manner as by means of the friction drive shown in Figure 2 of the drawing. Extend-

ing through one wall of the casing 11 is a horizontal shaft 30. Reinforcing washers 31 and 32 may be provided about the aperture through which the shaft passes. A roller 33 is secured to the inner end of the shaft, and a crank 34 having the handle 34' is secured to the outer end of the shaft. The drum rests on the roller 33, so that rotation of the shaft 30 by means of the handle 34' causes the drum to rotate.

As has been stated, the drum is adapted to carry about its cylindrical surface a strip which I have for convenience referred to as "continuity strip." The continuity may be any one of an infinite number of easy short stories for children, which may be chosen from the Bible, history, nursery rhymes, and even cartoons from newspapers. A number of continuities of various kinds and types may be furnished with each toy, and the child may be encouraged to make his own continuities, thereby stimulating his creative instinct.

In the illustrated embodiment, the continuity strip is indicated by the numeral 35, and has depicted thereon in a series of vertical panels a sequence of pictures and legends of a cartoon such as generally appears in the Sunday newspapers. The pictures run consecutively from right to left so that when mounted on the drum, rotation of the handle in a forward direction will bring the pictures into registration with the window 13 from left to right.

The strip of pictures may be secured permanently or detachably to the circumference of the drum in any suitable manner. In the illustrative embodiment, the strip is detachably secured so that different strips may be used with the same drum. A band of paper 36 or other material is adhesively secured to the vertical flange of the upper lid 16, and a similar strip 37 is adhesively secured to the vertical cylindrical portion of the lower lid 17. These bands are somewhat wider than the flanges of the two lids, thereby providing an upper annular groove 38 and a lower annular groove 39. The continuity strip is just long enough to go entirely around the drum, and its marginal edges are adapted to be received in the annular grooves 38 and 39, thereby holding the strip in place. In the case of a relatively stiff continuity strip, it may be necessary to remove the upper lid 16 before mounting the strip on the drum. The strip is passed around the drum with its lower marginal edge in the lower groove 39 and

then the lid is replaced. The flange of the lid 16 then holds the strip in place.

For commercial purposes, a number of additional strips carrying different subjects may be provided with each device. These additional strips may be stored in the drum 14. In Figures 2 and 3, a number of strips 40 and 41 are shown stored in the drum.

It will be understood from the foregoing description that inherent curiosity will stimulate a child to turn the handle 34' and thereby to produce the effect of motion pictures. The child will be further stimulated to memorize the pictures and/or words and to test his memory as he turns the drum. The fact that the parts of the device are separable will encourage the child to take it apart and to put it together again, thereby strengthening his instinct of construction or contrivance. He will also be encouraged or stimulated to change the continuity from time to time, and to make his own continuities, as by pasting the individual pictures from a cartoon on a horizontal strip.

The foregoing description is given by way of illustration and not of limitation, and no limitations are to be imported into the claim unless required by the state of the prior art.

I claim:

A toy of the character described comprising a casing having a window in a vertical wall thereof, a vertical shaft journaled between the top and bottom of said casing, a cylindrical drum mounted on said shaft for rotation within said container, said drum having depicted on its cylindrical surface a sequence of events, and means to rotate said drum so as to bring each event in sequence into registration with said window, said means consisting of a horizontal shaft extending into said casing through one wall thereof with its inner end in contact with the bottom of said cylindrical drum, and a crank at the outer end of said shaft for turning said shaft.

CHARLES O. WALLS.
